UNITED STATES PATENT OFFICE.

WARREN N. HUNTER, OF CHICAGO, ILLINOIS, ASSIGNOR TO UNION SPECIAL MACHINE COMPANY, OF CHICAGO, ILLINOIS, A CORPORATION OF ILLINOIS.

BAG.

995,869.

Specification of Letters Patent. Patented June 20, 1911.

Application filed August 11, 1908. Serial No. 447,937.

To all whom it may concern:

Be it known that I, WARREN N. HUNTER, a citizen of the United States, residing at Chicago, in the county of Cook, State of Illinois, have invented certain new and useful Improvements in Bags, of which the following is a description, reference being had to the accompanying drawing and to the letters and figures of reference marked 10 thereon.

My invention relates to an improvement in bags, and particularly to a device for enabling the closing seam of the bag to be readily severed, the bag opened and the contents removed, without in the breaking of the seam endangering the structure of the bag itself.

Manufacturers of cement make a practice of selling the same in bags which are filled 20 and closed at the top by seaming. These bags are made of tough and strong material, and are of such cost that it is desirable they should be used over and over again. Through the carelessness of workmen in opening 25 these bags by using shovels or other tools for severing the closing seam, a considerable percentage of loss of bags is occasioned the cement manufacturers, by very materially limiting the number of times a bag may be 30 used.

It is the object, therefore, of my invention to provide a simple and effective attachment to the bag for severing the seam, which will be within easy reach of a workman, and be 35 much easier to manipulate than a tool.

The invention, therefore, consists primarily of a bag having a closing seam readily ravelable, when severed, and means attached to the bag, adapted when manipulated to sever the closing seam.

Secondly, it consists of a bag having a closing seam readily ravelable when severed, and a device attached to the bag and engaged by the stitches of the closing seam, 45 whereby when strain is put on said device, the seam may be broken.

Finally, the invention consists in the various matters hereinafter described and referred to in the appended claims.

The invention is illustrated in the accompanying drawings, in which,—

Figure 1 is a side view of a bag constructed in accordance with my invention, and Fig. 2 is a view, partly in perspective, showing the bag after the seam has been 55 severed and partly unraveled. Fig. 3 is a cross section of the bag.

In these drawings, A represents the bag, which may be of any suitable material. After it is filled, it is closed by a seam a, formed as herein shown, of a line of single chain stitching, which from its nature is easily ravelable when broken. Secured on the outside of the bag near one end of the seam, and by certain of the stitches of the seam, is a strip of material b. This may be of the same material of which the bag is composed, or of some other material, the only essential being that it be stronger than the seam, and capable of breaking or severing the same, when 70 strain is applied.

While the construction illustrates a practical embodiment of my invention, it will be understood that I do not desire to limit myself to the exact details of construction.

Having thus described my invention, what I claim as new and desire to secure by Letters Patent, is:—

1. A bag having closing means for the mouth thereof and a separate strip arranged 80 exteriorly of the bag and secured thereto by said mouth-closing means, whereby the removal of the strip will break the closing means.

2. A bag having a closing seam readily 85 ravelable when severed, a strip of material attached to the bag by some of the stitches of the closing seam, and adapted when strain is put upon it to break the seam.

In testimony whereof I affix my signature, 90 in presence of two witnesses.

WARREN N. HUNTER.
